UNITED STATES PATENT OFFICE

JULIUS SIRIMAY, OF PHILADELPHIA, PENNSYLVANIA, ASSIGNOR TO JACQUARD KNITTING MACHINE COMPANY, INC., OF PHILADELPHIA, PENNSYLVANIA, A CORPORATION OF NEW YORK

CIRCULAR KNITTING MACHINE

Application filed May 29, 1930. Serial No. 457,213.

The objects of my invention are to provide improved dogless and racking mechanisms, and an improved combined dogless and racking mechanism for circular rib knitting machines.

The nature of the improvements in the dogless will be best understood from the following description of the embodiment illustrated in the accompanying drawings.

- 10 For racking, one of the needle beds (here, specifically, the dial) is provided with mechanism, such for example as gear mechanism, for turning it both forward and back considerable distances (unlimited distances if desired) independently of the other needle bed. Mechanism is also provided for actuating a cam or cams of one of the beds to secure the retraction of all of the needles of that bed preliminary to racking; mechanism to 15 angularly displace the knitting wave of one bed with respect to that of the other will accomplish the same result; the purpose is to have the needles out of such interlocking relation as will prevent racking. The arrangement is such that the racking may be 20 done without stopping the machine, i. e., while the needle cams continue to revolve. Such yarn cutters and holders may be provided that the feeding of all yarns can be 25 stopped during the racking operation; in which case the needle cams of both beds are made so adjustable that the needles of both beds are held inoperative as it were, i. e. inoperative to such an extent as to avoid casting 30 off during the racking operation. In the alternative, knitting may be continued at one needle bed the needles of the other bed being held entirely out of action; the yarn or yarns are then not cut. Preferably the mechanism 35 for turning the racking needle bed is so arranged that it turns that bed a definite measured distance each time it is called into operation, say the distance from centre to centre of adjacent cylinder needles; thereby each 40 racking operation is caused to terminate with the dial and cylinder needles in proper relative positions for further knitting. It will be so observed that so far as my invention 45 concerns racking, the invention can be ap-

plied to racking the cylinder as well as racking the dial.

In my combined dogless and racking mechanism, the external member to which the dial is locked is itself mounted for movement 55 around the axis or centre line of the dial and cylinder, and the racking mechanism mentioned above is applied to this external member.

In the accompanying drawings illustrating 60 an embodiment of my invention: Figure 1 is an elevation, partly in section, of a part of a circular rib knitting machine, with the invention applied thereto, using latch needles. Figure 2 is a plan view, partly in section. Figure 3, a detail, is a sectional view of a part of the mechanism for racking the dial. Figure 4 is an elevation of substantially the same part of this mechanism, the showing being from the left in Figure 2. 65 Figure 5 is an elevation of the yarn changing mechanism selected for illustrative purposes. Figure 6 is a plan view of the latter. Figure 7 is a plan view of a selected mechanism for moving the dial needle cam into and out 70 of operative position. Figure 8 is an elevation of selected mechanism for dropping a raising cam for the cylinder needles out of action.

While the drawings illustrate a single feed 80 machine in which the cylinder and dial are stationary, it will be evident that my invention is not entirely limited to these features.

In the drawings, the stationary needle cylinder and dial appear at 1 and 2 respectively; 85 the rotating cam cylinder and dial cam cap appear at 3 and 4 respectively. The top or a stationary member of the frame work is shown at 6.

The needle cylinder 1 and cam cylinder 3 90 can be assumed to be carried by the stationary frame of the machine in some ordinary manner, and the cam cylinder 3 is driven by the power shaft of the machine; the dial 2 and dial cam cap 4 are also supported in quite 95 an ordinary manner, that is to say, by a spindle 7 hung on the bracket 8 which is carried by posts 9 on the cam cylinder 3. The spindle 7 is pinned at 10 to a collar fastened to the dial 2, the cam cap 4 rests on the dial 2 100

and loosely encircles the spindle 7, and the latter is threaded to an adjusting nut 15 which bears on a combined radial and thrust bearing 16 resting on the top of the bracket 8. By turning the nut 15, the dial 2 may be raised or lowered with respect to the cylinder 1. The bracket 8 rotates with the cam cylinder 3 of course, and by means of the link 17 the cam cap 4 is caused to rotate synchronously; all quite in accordance with common practice.

To hold the dial 2 stationary (i. e. stationary with respect to cylinder 1) the spindle 7 is extended above the nut 15 by which it is supported, to a dogless mechanism carried by the annular bracket 18, which is supported by posts 19 on the stationary top or frame member 6 of the knitting machine. To lock the spindle 7, and hence the dial 2, against rotation along with the bracket 8, the upper end of the spindle is fastened against rotation to the ring 20 and the latter is surrounded by an annular member 21, (the two being separated a little distance as illustrated at 22 in Figure 1) and the two members 20 and 21 are at all times locked together by some of the latches 23; for the present, the annular locking member 21 can be regarded as held stationary in the bracket 18. For adjustment purposes, I directly key the spindle 7 (against rotation) to the collar 24, and connect this collar to the ring 20 by means of the pin 28, bracket 29 at ring 20, and the opposing bolts 30 between the bracket and pin 28; it will be apparent that by adjusting the bolts 30, the spindle, and thereby the dial 2, can be swung slightly one way or the other to place the dial needles in desired angular relation to the cylinder needles between which they project. The annular locking member 21, rests on the upper annular surface 31 of the bracket 18; except for the fact that racking is provided for in the mechanism illustrated, this member 21 might be permanently fastened to the bracket 18, or be the bracket 18 itself. The cooperating ring 20 (to which the collar 24 is fastened) rests on a rotating annular latch-operating member 32, which is carried by the lower annular supporting surface 33 of the bracket 18 and which, through its collar 34 and clamp 35, is driven by the pin 36 which rises from the bracket 8; the member 32 rotates synchronously with the cam cylinder and dial cam cap therefore. To drive the racking mechanism, the outer edge of this annular member 32 is provided with gear teeth as illustrated; as a part of the dogless mechanism per se, it is essentially the operator of the latches 23, for which purpose it is provided with a cam race as indicated at 37, into which extend pins 38 carried by the sliding latches 23. Except opposite the perforation or perforations in the latch-operating member 32 (such as at 43) through which the yarn or yarns are led, this race 37 may be

substantially circular in shape, and located substantially below the space 22 between ring 20 and locking member 21, as appears in Figs. 1 and 2. At one or more places 43, at the same distance from the centre line of the spindle 7 as the space 22, the latch operator 32 is pierced with one or more holes through which the yarn passes from the cones on the yarn carrier 44 on its way to the yarn guides and needles; the circular member 45 is simply to hold the yarns away from the more central mechanism in passing through these holes at 43 to the yarn guides feeding the needles of the cylinder 1 and dial 2. As shown in Figure 2, the race 37 is carried inwardly toward the spindle 7, opposite the point or points 43 where the latch operator 32 is perforated for the yarns. There being more latches 23 than there are guides 43, or the latches being properly placed with respect to these guides 43, it is obvious that some of the latches will be held in position to fix ring 20 to locking ring 21 at all times (position of the latch 23 in Fig. 1), but that each latch will be forced back entirely into ring 20 each time one of the guideways 43 comes to the respective latch, and thus the yarns permitted to pass the latches. The bobbin or yarn cone holder 44 may be supported by legs 48 rising from a ring 46, which rests on a circular ledge 47 projecting outwardly from the ring 20, as shown in Figures 1 and 2; at say each point 43, ring 46 is fastened to the latch operator 32, and thus caused to turn with this latch operator and the cam ring 3 and dial cam cap 4.

In order to rack the dial 2, I have provided the worm 51 and its accessory mechanisms, the worm 51 gearing into corresponding teeth in the outer edge of the locking member 21, and thus serving to turn this locking ring 21 forward and back, and also to hold this locking ring stationary when the worm is at rest. It is obvious that by shifting the locking ring 21 one way or the other, the dial 2 is shifted correspondingly with respect to cylinder 1. Preferably the auxiliary and driving mechanism for the worm gear 51 is such, as before indicated, that each time the worm is called into rotation, it is rotated just far enough to shift the dial 2 a certain predetermined angular distance, say (and usually) the distance between centers of adjacent cylinder needles. To rack the dial greater distances, the worm is then called into action repeatedly as many times as may be necessary. To drive the worm 51 in this manner, I preferably provide a Geneva wheel 52 mounted on the worm shaft, and two pins 53 and 54 for turning the Geneva wheel 52, these pins 53 and 54 being mounted on oppositely rotating disks 55 and 56 and provided with mechanism, properly controlled, for sliding the two disks along their own axis to bring either 53 or 54 into cooperation with 130

Geneva wheel 52, and thereby turn it one way or the other; in their mid-position shown in Figure 2, both pins 53 and 54 are out of contact with the Geneva wheel 52, and hence the latter (and the dial 2) are at rest. In the preferred embodiment of my invention illustrated, these two pin disks 55 and 56 are driven constantly, so long as the main drive shaft of the knitting machine is in operation, through connection to the latch operating member 32. As before pointed out, this latch-operating member 32 is in continuous rotation through its connection to the bracket 8 rising from the cam cylinder 3. To operate the racking mechanism, this latch-operating member is provided with gear teeth on its outer edge, and is engaged by a gear 57 which in turn drives gear 58, the latter driving 59 which is fastened to a shaft 60 carrying the miter gear 61. The two miter gears 62 and 63 are in continuous mesh with the miter gear 61 for driving thereby; gear 62 is keyed to shaft 64, and the latter in turn is keyed to the sleeve 65 from which the disk 55 projects; miter gear 63 on the other hand is carried by sleeve 66, rotatable on shaft 64, and fastened to outer sleeve 67, which in turn is keyed to a sleeve 68 mounted on, but free to turn on, an extension of sleeve 65, as appears most clearly in Figure 3. As a result of this connection, the two pin disks 55 and 56 are driven continuously from the main drive shaft of the knitting machine, and because of the miter gear arrangement, the two pin disks rotate in opposite directions. For positioning the pins 53 and 54 with respect to Geneva wheel 52, the sleeve 65, and therewith the sleeve 68, is slidable on the shaft 64; sleeve 68 is slidably keyed to the outer sleeve 67. By sliding sleeve 65 therefore, either pin 53 or 54 can be brought into position to turn the Geneva wheel 52. For sliding this sleeve 65, mechanisms of various types can be provided obviously. Preferably I provide this sleeve with two oppositely facing circular cams 72 and 73 as shown in Figures 2 and 3. In the mid-position of this sleeve 65 (when both pins 53 and 54 are out of engagement with Geneva wheel 52), a sliding pin 74 projects between the two cams 72 and 73, as illustrated in Figure 2; obviously pin 74 in cooperation with cam 72 and 73 retains sleeve 65 in this mid-position and brings the sleeve back to this mid-position should it tend to depart therefrom. Pin 74 is pushed toward the sleeve 65 by coil spring 75, and is accompanied by the two parallel sliding pins 76 and 77, which are tied together for joint operation in opposite directions by the lever 78 pivoted at 79. It will be observed that the pins 76 and 77 are provided with projecting shoulders 80, located between shaft 64 and collar 81 on pin 75, whereby pin 74 is retracted from between cams 72 and 73, each time either pin 76 or pin 77 is moved into position between these cams (Figure 3). The shoulders 80 are fixed to pins 76 and 77 respectively, and collar 81 is fixed to pin 74; also the collar and shoulder 80 of pin 76 are so related that when this pin is retracted toward its position in Fig. 3, the shoulder 80 on this pin 76 strikes collar 81 and therethrough carries pin 74 to its retracted position of Fig. 3; the collar and shoulder 80 of pin 77 are related in the same manner, so that retraction of pin 77 also produces retraction of pin 74; when both pins 76 and 77 are in their mid-positions (positions of Figs. 1 and 2) the shoulders 80 let the collar 81 move so far toward shaft 64 that pin 74 is moved (by spring 75) into its projected position (Fig. 2). From a pattern mechanism 84 rise two rods 85 and 86 attached to rocker arms 87 and 88 of rock shafts 89 and 90, which carry respectively rocker arms 91 and 92 for engagement with the sliding pins 76 and 77. When the shaft 64 of this racking control mechanism has been turned 180 degrees from its position in Figure 2, it is apparent that the pattern mechanism 84 may raise the connecting rod 86 and thus thrust pin 77 into its position in Figure 3, wherein it rests between the two cams 72 and 73; this action withdraws pin 74 from between these cams, for reasons before pointed out. The continued rotation of shaft 64 then brings cam 73 to bear on this pin 77, and this in turn pushes sleeve 65 (and therewith sleeve 68) to the position shown in Figure 3; that is to say into the position where pin 53 engages the Geneva wheel 52. The pattern mechanism may release the rod 86 as soon as the shaft 64 has turned far enough to place cam 72 underneath sliding pin 74; when this happens spring 75 pushes pin 74 against this cam, and this in turn tends to retract pin 77, but because cam 72 prevents full projection of pin 74, pin 77 remains in about the position illustrated in Fig. 3 until shaft 64 has turned about 180 degrees from its position in that figure; that is to say, about one complete revolution from the time pin 77 was thrust toward shaft 64. Each time the pattern mechanism raises rod 86 therefore, the pin 53 is caused to notch the Geneva wheel 52 around one step, and unless rod 86 is then raised again, pin 74 slips into place between cams 72 and 73 (Figure 2), thereby retracting pin 77 and in cooperation with cam 72 returning sleeves 65 and 68 to their initial positions of Figure 2. The notches in the Geneva wheel 52 are so placed that each step (or turn of the Geneva wheel 52 from one notch to another) serves to turn the worm 51 just far enough to move the dial the desired predetermined distance. From this explanation it will be apparent that the pattern mechanism 84 by raising rod 85 in lieu of rod 86, can cause the sleeves 65 and 68 to be moved in the opposite direction, 130

bringing pin 54 into cooperation with the Geneva wheel 52, and thereby the dial 2 racked in the opposite direction.

Inasmuch as the whole dial is racked in one step, it is necessary that the dial needle knitting wave and the cylinder needle knitting wave be taken out of their normal interlocking relation. In the present instance the dial needles are held retracted during the racking operation, and for this purpose, the dial needle projecting cam 98 (Figure 7) may be pivoted to the dial cap 4, and provided with a pin 99 engaged by lever 103, also pivoted on the dial cap 4, and connected to shaft 100 rising from the cam cylinder 3, the latter being provided with two projecting levers 101 and 102, pivoted to the cam cylinder 3, for rocking it back and forth. When the lever 101 is thrust inwardly to the position illustrated in Figure 7, the dial needle cam 98 is in the position illustrated in that figure, and the dial needles are projected to take on yarn in the usual way; on the other hand, when the lever 102 is thrust inwardly (and thereby shaft 100 rocked and lever 101 thrust outwardly) the dial cam 98 is turned to its inner position wherein the dial needles are allowed to ride through it without being projected. It will be understood that in a multi-feed machine, the dial needle projecting cam at each feed may be put out of action as a pre-requisite to racking. Also, since I contemplate racking the dial while the cam cylinder 3 and dial cam cap 4 continue in rotation, I provide yarn guiding and holding mechanism for taking all yarns out of action. Such is the yarn mechanism at 105, which is designed to handle two yarns. The yarn guides 106 and 107 are in the form of levers pivoted at 108. Above the level of the pivot 108, two levers 109 and 110 cooperate with the yarn fingers 106 and 107 respectively, to turn these fingers outwardly (position of finger 106 in Figure 5); likewise, below the level of the pivot 108 two similar levers 111 and 112 cooperate with these fingers to thrust the latter inwardly to yarn feeding position (position of finger 107 in Figure 5). Since all yarns are put out of operation when the dial is being racked, a yarn scissor and holder is provided for each yarn; in the present instance scissor and holder 113 serves the yarn of finger 106 and scissor and holder 114 serves the yarn of finger 107. By pushing in projecting finger lever 115, depending lever 116 is actuated to open the scissor and holder 113; similarly pushing in finger lever 117 actuates depending lever 118 to open scissor and holder 114; when these finger levers 116 and 117 are released, springs 119 close the yarn holders and scissors and restore the operating levers to the positions illustrated. It will be understood that corresponding scissors and yarn holders are provided at each of the feeds, on a multi-feed machine.

Where all yarns are taken out of action during the operation of racking the dial, it is necessary that the needles of both the dial and the cylinder be held inoperative during the racking operation, or at least so inoperative as not to cast off their stitches. Assuming the dial needles are to be retracted to withdraw them from between the cylinder needles, this is sufficient for the needles of this bank. The raising cam (or cams) for the cylinder needles may then be dropped down so far that the cylinder needles are not raised high enough thereby to drop their loops behind their latches. For this purpose (see Figure 8) the cylinder needle raising cam 122 may be carried on a sliding rod 123, mounted in the cam cylinder 3, and provided with a rack 124 and cooperating rack sector 125 for raising it into its high position wherein it is capable of raising the cylinder needles to such heights that the loops drop behind the latches, and a latch 126, pivoted at 127 in the cam cylinder 3 to project underneath the rack 124 to hold the needle cam raised against the tension of the spring 128; an operating finger 129 may serve to turn the rack sector 125 when thrust (from right to left) to the position illustrated in Figure 8. It will be understood that the cylinder needle raising cam of each feed, of a multi-feed machine, may be actuated in the same manner, i. e. be dropped to a relative inoperative position, as a pre-requisite to racking the dial.

Bob-pins may be used to move or control the various parts before mentioned. In the present instance, the bob-pin 131 has head carrying plates 132 and 133, to put the yarns out of action, and has three possible positions: low, middle and high. In its high position, plate 132 is in place to be struck by finger lever 109 and thus throws yarn finger 106 out of action, and plate 133 is in position to strike finger lever 115 and thus actuate the yarn holder and scissor 113. In its middle position, plate 132 is in position to be struck by the finger lever 110 and thus throw yarn finger 107 out of action; at the same time plate 113 is in position to actuate finger lever 117 and thus the yarn scissor and holder 114. In the low position of this bob-pin, plates 132 and 133 are entirely out of action. In the same manner, bob-pin 134 carries plates 135 and 136 for actuating finger levers 111 and 112, and simultaneously 115 and 117 for putting the yarns into action. Another bob-pin (not shown) is provided with plate 137, which also has three positions. In its high position it is in position to be struck by finger lever 101; in its middle position, to be struck by finger lever 102 of the dial cam 98, and in its low position, is inoperative. Likewise another bob-pin has a plate 138, which in one elevated position actuates operating arm 129 of cylinder cams 122, in its middle position pushes the latch 126

from under the rack 124, and in its low position is inoperative. All these bob pins may be controlled by the same pattern mechanism 84. The exact nature of the pattern mechanism 84 is not material to the invention. The relative positions and extents of the bobpin plates illustrated in Figure 2, indicate the relative sequence of operations of the members they actuate as the cam cylinder 10 and dial cam cap rotate and bring the various finger levers into contact with these plates. In brief, preliminary to racking, the cylinder needle cams are depressed usually slightly before the dial needle cams are taken 15 out of action. When a yarn is to be thrown out of action by plate 132, its yarn holder and scissor are opened before the yarn is taken out of action and held open until the respective yarn finger is thrown completely 20 to its outermost position. When a yarn is to be put into operation by plate 135, the corresponding yarn holder is actuated a little later by plate 136. The removal of the yarns from action, preliminary to racking, is substantially simultaneous with taking the needle 25 cams out of action.

It will be understood that my invention is not limited to the detailed construction illustrated and described above, except as appears hereinafter in the claims.

I claim:

1. In a circular rib knitting machine having a stationary needle cylinder and dial, and a rotating cam cylinder and dial cam cap, a spindle carrying the dial and dial cam cap, a bracket mounted on the cam cylinder carrying said spindle, a bracket mounted on a stationary part of the knitting machine, and dogless mechanism including means engaging the spindle to hold the same against rotation carried by the last mentioned bracket. 35 2. In a circular rib knitting machine having a stationary needle cylinder and stationary dial, and rotating cam cylinder and dial cam cap, a spindle carrying said dial and dial cam cap, a bracket mounted on a rotating cam cylinder and carrying said spindle, a bracket mounted on a stationary part of the knitting machine and substantially surrounding an end of said spindle projecting above the first mentioned bracket, a member fastened to the upper end of said spindle against rotation thereabout but free of the weight of the dial and dial cam cap, movable 45 latches for locking said member to said bracket mounted on a stationary part of the machine, a rotating latch-operating member mounted on the latter bracket, and means connecting said latch-operating member to the said cam cylinder for rotation thereby. 50 55 60

3. The subject matter of claim 2 characterized by the fact that said member which is fixed to the upper end of said spindle against rotation thereabout, comprises a ring surrounding the spindle and means connecting

said ring to the spindle providing for annular adjustment of the spindle with respect to said ring.

4. In a circular rib knitting machine, having a stationary needle cylinder and stationary dial, and a rotating cam cylinder and dial cam cap, a spindle supporting the dial and dial cam cap, a bracket mounted on said cam cylinder supporting said spindle, a bracket mounted on a stationary part of the knitting machine and substantially surrounding an end of the spindle projecting beyond the first mentioned bracket, a member surrounding the upper end of the spindle and fixed thereto against rotation but free of the weight of said dial and dial cam cap, sliding latches locking said member to the second mentioned bracket, a latch-operating member carried by the second mentioned bracket, having a cam race for operating said latches, said member which is fixed against rotation with respect to said spindles being mounted on said latch-operating member, and means connecting said latch-operating member to said bracket mounted on the cam cylinder for rotation thereby. 70 75 80 85 90

5. The subject matter of claim 4, characterized by the fact that there is a carrier for the yarn cones, and this yarn cone carrier is supported by the said latch-operating member. 95

6. In a circular rib knitting machine, the combination of two cooperating circular needle beds, a series of gear teeth fastened to one of said beds and disposed substantially coaxially therewith for racking said bed, a gear to mesh with said series of teeth, and means for intermittently actuating said gear at will to rack the last mentioned needle bed with respect to the other. 100 105

7. In a circular rib knitting machine, the combination of two cooperating circular needle beds, a gear connected to one of said beds, a gear meshing with the first mentioned gear to operate the latter, and means to turn the last mentioned gear definite predetermined angular distances to rack the needle beds corresponding distances one with respect to the other. 110

8. In a circular rib knitting machine, the combination of two cooperating circular needle beds, a series of gear teeth fastened to one of said beds and disposed substantially coaxially therewith for racking said bed, a gear to mesh with said series of teeth, and means to turn said gear definite predetermined angular distances intermittently at will to rack the last mentioned needle bed corresponding angular distances with respect to the other needle bed. 115 120 125

9. In a circular rib knitting machine, the combination of two needle beds, means for racking one of said beds with respect to the other, said means including a Geneva wheel and a pin wheel for turning the Geneva 130

wheel, and means for putting the pin wheel into operative relation to the Geneva wheel.

10. In a circular rib knitting machine, the combination of two needle beds, means for racking one of said beds with respect to the other, said means including the Geneva wheel and a pair of constantly driven, oppositely rotating, pin wheels, and means for sliding said pin wheels axially to bring one or the other into operating relation to said Geneva wheel.

11. In a circular rib knitting machine having a stationary needle cylinder and dial, and a rotating cam cylinder and dial cam cap, the 15 combination of a dogless mechanism for holding the dial stationary with respect to the cylinder, said dogless mechanism including a locking member provided with gear teeth, a gear engaging said teeth and means 20 for turning said gear for racking the dial.

12. The subject matter of claim 11 characterized by the fact that said gear is a worm gear.

13. In a circular rib knitting machine having a stationary needle cylinder and dial, and a rotating cam cylinder and dial cam cap, the combination of a dogless mechanism for holding the dial stationary with respect to the needle cylinder, said dogless mechanism 25 including a movable locking member provided with gear teeth and a rotating latch-operating member, a gear meshing with the teeth of said locking member, and means for connecting said gear to said rotary latch-operating member at will for rotation thereby.

14. In a circular rib knitting machine having a stationary needle cylinder and dial, and a rotating cam cylinder and dial cam cap, the combination of a dogless mechanism for 40 holding the dial stationary with respect to the cylinder, said dogless mechanism including a movable locking member provided with gear teeth and a rotating latch-operating member, a worm gear meshing with the teeth 45 of said movable locking member, a continuously-rotating means driven by said latch-operating member, and clutch means for coupling said continuously rotating means to said gear to rotate the latter.

50 15. In a circular rib knitting machine, having two needle beds, racking mechanism for racking one of said beds as a whole with respect to the other, and yarn guiding and holding means for taking out of action and cutting all the yarns.

55 16. The subject matter of claim 15 characterized by the fact that means are provided to discontinue the knitting action on the needles of both beds during racking, to avoid 60 casting off.

In testimony whereof, I have signed this specification.

JULIUS SIRMAY.

CERTIFICATE OF CORRECTION.

Patent No. 1,891,956.

December 27, 1932.

JULIUS SIRNAY.

It is hereby certified that error appears in the printed specification of the above numbered patent requiring correction as follows: Page 5, line 46, claim 2, for the article "a" second occurrence read "the", and line 87, claim 4, for "spindles" read "spindle"; page 6, line 14, claim 11, strike out the article "the"; and that the said Letters Patent should be read with these corrections therein that the same may conform to the record of the case in the Patent Office.

Signed and sealed this 28th day of February, A. D. 1933.

M. J. Moore,
Acting Commissioner of Patents.
